DESIGN FOR A WHEELED ROCKING HORSE OR SIMILAR ARTICLE

Alfred H. Hanscom, Chicago, Ill.

Application February 11, 1944, Serial No. 112,536

Term of patent 7 years

(Cl. D34—15)

To all whom it may concern:

Be it known that I, Alfred H. Hanscom, a citizen of the United States and resident of Chicago, in the county of Cook and State of Illinois, have invented a new, original, and ornamental Design for a Wheeled Rocking Horse or Similar Article, of which the following is a specification, reference being had to the accompanying drawing, forming part thereof.

In the drawing,

Figure 1 is a perspective view of a wheeled rocking horse or similar article, showing my new design;

Figure 2 is a top plan view of the same.

When the article of the present design is used as a rocking horse the wheels are removed.

I claim:

The ornamental design for a wheeled rocking horse or similar article, as shown and described.

ALFRED H. HANSCOM.
